UNITED STATES PATENT OFFICE.

THOMAS NYGAARD, OF MINNEAPOLIS, MINNESOTA.

SEPARABLE FRAME.

Application filed March 28, 1924. Serial No. 702,614.

To all whom it may concern:

Be it known that I, THOMAS NYGAARD, a citizen of the United States, residing at Minneapolis, in the county of Hennepin and State of Minnesota, have invented certain new and useful Improvements in Separable Frames; and I do hereby declare the following to be a full, clear, and exact description of the invention, such as will enable others skilled in the art to which it appertains to make and use the same.

My invention provides what, for lack of a better name, is herein designated as a separable frame, but which, more accurately described, consists of a two-part frame or body, the members of which are separated by a parting channel and are connected by links or channel-bridging members, which, one at a time, will release to permit passage of an object through the parting channel, while, at the same time, a multiplicity of the bridge-acting links will hold the two frame or body members securely connected or locked together.

This improved device is thought to be broadly new; even as a new mechanical movement or as a device of general utility, and irrespective of any specific use. No attempt will be herein made to enumerate the various possible uses, except the one indicated in the drawings, wherein the device is shown as applied to connect brush members in such a manner that the brush may be pushed or drawn straddle of a seat leg, desk leg, post or the like.

The principle broadly involved in this invention is embodied in the device illustrated in the accompanying drawings, wherein like characters indicate like parts throughout the several views.

Referring to the drawings:

Fig. 1 is a plan view with some parts sectioned, illustrating the invention incorporated in a floor brush suitable for use in sweeping school floors;

Fig. 2 is a detail in section on the line 2-2 of Fig. 1; and Fig. 3 is a fragmentary view illustrating a modified form of the device.

In the particular adaptation of the invention illustrated, a right-hand series of floor brushes 3 are riveted or otherwise secured to a common bar 4 and a left-hand series of brushies 5 are likewise secured to a common bar 6. The bars 4 and 6, as shown, are preferably flat steel bars in parallel ar-

rangements, spaced to afford a parting channel 7. The bars 4 and 6 constitute the frame or body members or sections.

Channel-bridging and bar-connecting links 8 are pivoted to the bar 4, as shown, by small nut-equipped bolts 9, and similar links 10 are pivotally connected to the bar 6 by nut-equipped bolts 11. The links 8 and 10 are alternated longitudinally of the bars or frame members 4 and 6 and, preferably, each link comprises an upper and a lower flat metal strap placed one above and one below the bar to which they are pivoted, and preferably, also, light coiled springs 12 are placed on the pivot bolts and compressed between the nuts thereof and the top straps of the respective links, as best shown in Fig. 2. These coiled springs 12 have extended arms, one arm of each spring being anchored to the bar 4 or 6 and the other arm acting on a lug 13 on the cooperating link and exerting on said links yielding force tending to hold the same downward or forward in respect to Fig. 1. At their free ends, the links 8 and 10, between their upper and lower straps, are provided with small roller-equipped pins 14 that normally engage segmental slots 15 formed in the bars 6 and 4. The segmental slots 15 are formed on arcs of circles, the centers of which are coincident with the axes of the respective link pivots, so that any one link may be freely moved upward or rearward in respect to Fig. 1, against the tension of the cooperating springs 12. Pivotal movements of the links under the action of the springs 12, as shown, are limited by small stop pins 16 on the bars 4 and 6 and which, as shown, engage in segmental notches 17 in the short ends of the upper straps of the links.

It is highly important to note that the links 8 and 10 are slightly oblique to lines drawn perpendicular to the facing edges of the bars 4 and 6 and, moreover, that said links 8 are oblique in the one direction and the links 10 are oblique in the opposite direction, so that the links 8 and 10 are not parallel, but, on the contrary, stand at an angle to each other and together form a truss connection between the bars or members 4 and 6. The importance of this will be understood when it is considered that the bar 4 can be moved longitudinally in respect to the bar 6, or conversely, only by simultaneous oscillations of the connecting links

and by movements permitting the bars 4 and 6 to partake of parallel movements either toward or from each other. To illustrate this point more definitely, suppose that an attempt is made to move the bar in the direction of the arrow marked thereon in Fig. 1, ahead of the bar 6. The links 8 would tend to permit such movement by swinging backward at their free ends and causing the two bars 4 and 6 to approach each other, but the links 10 tend to permit such advance movement of the bar 4 by causing the two bars 4 and 6 to move farther away from each other, and obviously, these two conflicting lateral movements of the bars 4 and 6 cannot take place and, hence, the links 8 and 10 securely tie the bars 4 and 6 together and form a truss that will cause them always to partake of common longitudinal or traveling movements in either direction.

In the application of the invention as a floor brush, a suitable handle 18 is provided and this is shown as secured in the socket 19 of a bracket 20, the arms of which are rigidly secured to the bar or frame member 4. In Fig. 1, the legs of a school desk or seat or the like are shown in section and marked by the numeral 21.

It will now be assumed that the brush constructed as described is to be used as a floor brush and to simultaneously brush the floor on both sides of the legs 21. The complete brush is forced forward in the direction of the arrows marked on the bars 4 and 6 in Fig. 1, so that the links 8 and 10 will be thrown in succession against said legs. When any link is pressed against a leg, post or the like, its spring 12 will yield and the said link will move on its pivot, thereby carrying its roller-equipped stud 14 out of the cooperating segmental slot 15, thus permitting the leg to pass into the parting channel 7 and to be passed completely through said parting channel between the frame bars or members 4 and 6. To permit the links 8 and 10 to be moved completely over the respective bars 4 and 6, said bars are shown as provided with notches 22 into which the roller-equipped studs 14 may be moved. Of course, as soon as a particular pivoted link is released, its spring will throw it back again into interlocking engagement with the cooperating segmental notch 15.

Obviously, the device, working as described, will permit the brush to be moved straddle of and past a fixed object, such as a desk or chair leg, and, of course, it would also permit a moving post or object to pass through the parting channel or between the members of the frame or body.

From consideration of the above, it will be understood that if all of the connecting links should be simultaneously thrown into releasing positions, the two bars or frame

members would then be completely separated and there would be no provision for causing the links to automatically reconnect the same. However, the connecting links are such in number that there will always be a sufficient number thereof remaining operative to hold the two frame members connected while other links are moving to clear or permit the passage of the object going through the parting channel.

As already indicated, the use of this improved device broadly is not limited to its use in connection with a brush nor to any other one particular purpose, and it will be further understood that the invention is capable of use to connect frame or body members, whether spaced on straight, parallel or on concentric lines. The gist of the invention broadly is found in the arrangement whereby a plurality of links or channel-bridging connections serve to hold together two frame sections or body members, but wherein the individual links or channel-bridging connections are displaceable, one or several at a time and progressively to permit a post or other member to pass through or to be passed through the channel between the said frame sections or body members.

In the modified construction illustrated in Fig. 3, the body member 4^a is in the form of a ring secured by arms 23 to a revolving shaft 24. The outer body member 6^a is in the form of a ring but is concentric to the ring 4^a. These two annular body members 4^a and 6^a are connected by links 8^a and 10^a that correspond to the links 8 and 10 before described in all of their actions. Certain other parts illustrated in Fig. 3, that correspond to parts described in the structure illustrated in Figs. 1 and 2, are indicated by the same characters hitherto applied but with the added exponent ^a. In this arrangement, 21^a may be assumed to be a fixed post located between the members 4^a and 6^a and which will successively displace the links 8^a and 10^a when the two body members are rotated on the axis of the shaft 24.

What I claim is:

1. The combination with spaced body members, of a multiplicity of yielding body-coupling elements normally connecting said body members but displaceable, one or several at a time, to permit an object to pass between said members, the said coupling elements being automatically restored to coupling positions when relieved from pressure from the object passing between the said members.

2. The combination with spaced body members, of a multiplicity of displaceable links each being attached to one of said body members and having detachable interlocking engagement with the other of said members, said links being yieldingly held in interlocking positions but displaceable, one

- or several at a time, to permit an object to pass between said members while certain of the operatively positioned links hold the said body member connected. 5. The structure defined in claim 3 in further combination with stops limiting the movements of said links in directions toward their operative positions. 35
3. The combination with spaced body members, of a multiplicity of displaceable links alternately pivoted to said two body members and having detachably interlocking engagement with the members to which they are not pivoted, said links being yieldingly held in operative position but arranged to be progressively displaced, one or several at a time, to permit an object to pass between said body members while said body members are held together by certain of the links that are in operative positions. 6. The structure defined in claim 4 in further combination with stops limiting the movements of said links in directions toward their operative positions. 40
- 10
- 15
4. The combination with spaced body members, of a multiplicity of links alternately pivoted to said two body members and having detachable interlocking engagement with the members to which they are not pivoted, said links being yieldingly held in operative positions but arranged to be progressively displaced, one or several at a time, to permit an object to pass between said body members while said body members are held together by certain of the links that are in operative positions, the links that are pivoted to the one body member being at an angle to the links that are pivoted to the other body member, when the links are in operative position, thereby forming a truss that holds the said body members constantly spaced. 7. The structure defined in claim 3 in which said links at their free ends have studs and the said body members have segmental slots to receive said studs, the said segmental slots being struck on the arcs of circles, the centers of which are the axes of the pivots of the respective cooperating links. 45
- 20
- 25
- 30
8. The structure defined in claim 3 in which said links are made of upper and lower metal straps having studs connecting their spaced free ends, the said body members having segmental slots to receive said studs and the said segmental slots being struck from the arcs of circles, the centers of which are the axes of the pivots of respective cooperating links. 50
9. The structure defined in claim 1 in further combination with brushes connected to co said body members and adapted to be moved on opposite sides of an object. 55
10. The structure defined in claim 3 in further combination with brushes connected to said body members and adapted to be moved on opposite sides of an object. 65

In testimony whereof I affix my signature.
THOMAS NYGAARD.
